PILE FABRIC AND METHOD OF MAKING
SAME

Roy C. Amidon, Fort Plain, N. Y., assignor of
one-third to Walter S. Becker, Little Falls,
N. Y., and one-third to Lewis M. Fowler, St.
Johnsville, N. Y.

Application February 11, 1938, Serial No. 190,101
Renewed August 29, 1938

17 Claims. (Cl. 66—191)

My invention relates to the art of knitting and it particularly has for its object to provide pile fabric such as plush fabrics or carpet fabrics, that can be knit on rapid flat knitting machines without materially slowing down their operations.

Further it is an object to provide a pile fabric in which the pile-loop threads are not woven into the sinker-loops or warp chains but are held in place between adjacent rows of warp chains by inlay or cross-connecting threads which tie adjacent chains together.

Another object is to provide a method of knitting the fabric above referred to.

Other objects will in part be obvious and in part 15 be pointed out hereinafter.

To the attainment of the aforesaid objects and ends the invention still further resides in the novel details of construction, combination and arrangement of parts, all of which will be first 20 fully described in the following detailed description, and then be particularly pointed out in the appended claims, reference being had to the accompanying drawing, in which:

Fig. 1 is a magnified, detail face view of a 25 fabric according to the invention.

Fig. 2 is a detail side elevation of a portion of the structure shown in Fig. 1.

Fig. 3 is a detail elevation of a modification, shown somewhat diagrammatically on a reduced 30 scale.

In the drawing in which like letters of reference indicate like parts in all the figures *w* indicates the warp threads which are knit into parallel chains *w'* and which chains are connected 35 together by inlay thread *i*.

During the knitting operation pile-loop threads *l* are laid beneath the inlay thread *i* and hooked through between adjacent inlay runs to form pile-loops *l'* as best shown in Fig. 2. These loops 40 *l'* may be cut either on the plane of the arrow *x* or on the planes of the arrows *y*.

Of course the chain and inlay threads, during the knitting operation, are drawn tight enough so that the piles, formed by the loops *l'* when 45 cut, will be tightly held in place by the adjacent chains in one direction and by the adjacent inlay runs in the other direction.

If desired the underface of the fabric may be given a coat of suitable cement *c*, such as latex 50 or nitro-cellulose cement, further to bond the piles in place. Further if it is desired a base or backing *b* of any suitable kind (such for example as a coarse knit or woven fabric, or a rubber or rubberized sheet, etc.) may be cemented on or otherwise secured to the back face of the pile

fabric shown in Fig. 1 and Fig. 2 as has been indicated in Fig. 3.

The kind and thickness of the warp and inlay threads *w* and *i* respectively and the kind and thickness of the pile or pile-loop threads used 5 are limited only by the capacity of the knitting machine and its ability to handle them.

The method preferably used in making the above fabric is to knit the warp chains and inlays in the usual way on flat knitting machines 10 and at the same time lay the pile-threads in place over the inlays and hook the pile-threads in loops through between adjacent runs or lays 15 of the inlay, and drawing the chains and inlays sufficiently tight to hold the pile-loop in place, and at an appropriate time cut the loops to leave the piles.

While I have shown the preferred embodiment 20 of the invention, it will be obvious to those skilled in the art that modifications may be readily made without departing from the spirit of the invention, while remaining within the scope of the appended claims.

From the foregoing description, taken in connection with the accompanying drawing, it is 25 thought the invention and its many advantages will be clear to those skilled in the art.

What I claim is:

1. A knit pile fabric comprising a plurality of rows of warp chains cross-connected by runs 30 of inlay thread combined with pile threads underlying the runs of inlay thread between the adjacent rows of warp chains and extending up between the adjacent runs of inlay thread to form between the adjacent runs of inlay thread to form 35 piles.

2. A knit pile fabric comprising a plurality of rows of warp chains cross-connected by runs of inlay thread combined with pile threads underlying the runs of inlay thread between the adjacent rows of warp chains and extending up between the adjacent runs of inlay thread to form 40 piles, and a suitable cement applied to the back or underface of the aforesaid structure, for purposes described.

3. A knit pile fabric comprising a plurality of rows of warp chains cross-connected by runs of inlay thread combined with pile threads underlying the runs of inlay thread between the adjacent rows of warp chains and extending up between the adjacent runs of inlay thread to form 45 piles and a base sheet secured to the back or underface of the aforesaid structure.

4. A knit pile fabric comprising a plurality of rows of warp chains cross-connected by runs of inlay thread combined with pile threads underly- 50

ing the runs of inlay thread between the adjacent rows of warp chains and extending up between the adjacent runs of inlay thread to form piles and a base sheet secured to the back or underface of the 5 aforesaid structure by means of a suitable cement.

5. The method of manufacturing pile fabric which comprises knitting parallel rows of warp chains, cross-connecting the same by inlaid 10 thread, placing pile-loop threads between adjacent rows of warp chains and under the cross runs of the inlay thread and looping the pile-loop threads through between adjacent runs of inlay thread.

15. 6. The method of manufacturing pile fabric which comprises knitting parallel rows of warp chains, cross-connecting the same by inlaid thread, placing pile-loop threads between adjacent rows of warp chains and under the inlay 20 thread and looping the pile-loop threads through between adjacent runs of inlay thread, and cutting the pile-loop to leave the piles.

7. The method of manufacturing pile fabric which comprises knitting parallel rows of warp 25 chains, cross-connecting the same by inlaid thread, placing pile-loop threads between adjacent rows of warp chains and under the inlay thread and looping the pile-loop threads through between adjacent runs of inlay thread, and re- 30 taining the pile-loop threads in place by drawing the warp chains and inlay thread tight.

8. The method of manufacturing pile fabric which comprises knitting parallel rows of warp chains, cross-connecting the same by inlaid 35 thread, placing pile-loop threads between adjacent rows of warp chains and under the inlay thread and looping the pile-loop threads through between adjacent runs of inlay thread, and cutting the pile-loop to leave the piles and retaining the pile-loop threads in place by drawing the 40 warp chains and inlay thread tight.

9. The method of manufacturing pile fabric which comprises knitting parallel rows of warp chains, cross-connecting the same by inlaid 45 thread, placing pile-loop threads between adjacent rows of warp chains and under the inlay thread and looping the pile-loop threads through between adjacent runs of inlay thread and giving the back of the fabric a coat of cementitious ma- 50 terial.

50. 10. The method of manufacturing pile fabric which comprises knitting parallel rows of warp chains, cross-connecting the same by inlaid thread, placing pile-loop threads between adjacent rows of warp chains and under the inlay thread and looping the pile-loop threads through between adjacent runs of inlay thread and se- 55

curing to the aforesaid structure a suitable back-ing sheet.

11. The method of manufacturing pile fabric which comprises knitting parallel rows of warp chains, cross-connecting the same by inlaid 5 thread, placing pile-loop threads between adjacent rows of warp chains and under the inlay thread and looping the pile-loop threads through between adjacent runs of inlay thread and giving the back of the fabric a coat of cementitious 10 material and securing to the aforesaid structure 1 a suitable backing sheet.

12. A knit pile fabric comprising a plurality of rows of cross-connected warp chains, com-bined with pile threads lying between adjacent 15 warp chains and underlying the cross-connect-ing threads and extending up between adjacent cross-connecting threads to form piles.

13. A knit pile fabric comprising rows of chain loops cross-connected by threads running from 20 chain to chain, and pile threads underlying the cross-connecting threads and looped through spaces between the chains and the cross-connecting threads thereby forming pile loops on one side of the fabric. 25

14. A knit pile fabric comprising rows of chain loops cross-connected by threads running from chain to chain, pile threads underlying the cross-connecting threads and looped through spaces between the chains and the cross-connecting 30 threads thereby forming pile loops on one side of the fabric, and means on the face of the fabric opposite said one side to secure the pile threads and the chains together.

15. The method of manufacturing pile fabric 35 which comprises knitting parallel rows of warp chains, cross-connecting the same by inlaid thread, placing pile-loop threads between adjacent rows of warp chains and under the cross runs of the inlay thread and looping the pile-loop threads through spaces between the adjacent runs of inlay thread to leave pile loops on one face of the fabric, the loops lying in rows between and parallel to the warp chains. 40

16. The method of manufacturing a pile fabric, 45 which comprises knitting cross-connected wales, placing pile-loop threads between adjacent wales and under the runs of cross-connecting threads and looping the pile-loop threads through be-tween adjacent runs of cross-connecting threads. 50

17. A knit pile fabric comprising a plurality of cross-connected wales, combined with pile threads lying between adjacent wales and under-lying the cross-connecting threads and extending up between adjacent cross-connecting threads to 55 form piles.

ROY C. AMIDON.
